UNITED STATES PATENT OFFICE

143,730

DESIGN FOR AN AIRPLANE

Randolph F. Hall, Rochester, and Edgar P. Rhodes, Clarence, N. Y., assignors to Bell Aircraft Corporation, Buffalo, N. Y.

Application October 16, 1943, Serial No. 111,391

Term of patent 14 years

(Cl. D71—1)

To all whom it may concern:

Be it known that we, Randolph F. Hall and Edgar P. Rhodes, citizens of the United States, residing at 638 Post Avenue, Rochester, county of Monroe, State of New York, and at Greiner Road, Clarence, county of Erie, State of New York, respectively, have invented a new, original, and ornamental Design for an Airplane, of which the following is a specification, reference being had to the accompanying drawings, forming a part thereof.

Figure 1 is a top plan view of an airplane showing our new design;

Figure 2 is a side elevational view;

Figure 3 is a front elevational view; and Figure 4 is a rear elevational view thereof.

We claim:

The ornamental design for an airplane, as shown.

RANDOLPH F. HALL.
EDGAR P. RHODES.
